EXERCISE APPARATUS

Robert R. Spackman, Jr., and Marvin E. Johnson, Carbon-dale, Ill., assignors to Southern Illinois University Foundation, Carbondale, Ill., a corporation of Illinois

Filed June 22, 1964, Ser. No. 80,493

Term of patent 14 years

(Cl. D34—5)

FIG. 1 is a view in perspective of an exercise apparatus embodying our new design;

FIG. 2 is a side elevation of our exercise apparatus as viewed from either side;

FIG. 3 is a rear elevation of our exercise apparatus; FIG. 4 is a front elevation of our exercise apparatus; FIG. 5 is a top plan view; and FIG. 6 is a bottom plan view.

We claim:

The ornamental design for an exercise apparatus, substantially as shown.
